UNITED STATES PATENT OFFICE.

ALOUIS L. WINNEGA, DECEASED, LATE OF PRESTON, MINNESOTA, BY LILY M. WINNEGA,
ADMINISTRATRIX, OF PRESTON, MINNESOTA, ASSIGNOR TO OSCAR W. CLARK, OF
CRESO, IOWA.

GATE-LATCH.

1,227,863.

Specification of Letters Patent.

Patented May 29, 1917.

Original application filed May 3, 1915, Serial No. 25,553. Divided and this application filed September 25, 1916. Serial No. 122,154.

To all whom it may concern:

Be it known that ALOUIS L. WINNEGA, deceased, late a citizen of the United States residing at Preston, county of Fillmore, 5 State of Minnesota, did invent a new and useful Gate-Latch, of which the following is a specification.

This invention relates to gate latches.

My object is to provide an improved latch 10 for gates, particularly those which are vertically movable and are adapted to swing, and to that end, it consists of improved rockably mounted latches adapted to engage a latching bar; and, further, a locking device of improved construction combined with the latch in a novel manner.

A practical embodiment of the invention is set forth hereinafter and disclosed in the accompanying drawings, in which—

20 Figure 1 is an elevation of a gate equipped with the improved latch, the gate being locked in lowered position;

Fig. 2 a similar view, the gate being unlatched in raised position;

25 Fig. 3 an enlarged detail perspective of the latch when freed or released; and

Fig. 4, a detail plan view, partly in dotted lines, showing the manner of locking the latch.

30 To illustrate the adaptability of the invention to a vertically movable swinging gate, it is shown thereon in Figs. 1 and 2.

The sill (which may be omitted) is shown at 1, the posts at 2, eyebolts 3 rotatable and 35 slidable within tube 4 of gate 5. The tube is secured to the gate by brackets 6.

To the latching post is secured a vertical latching rod 7.

40 The latches 8 and 9 are rigidly secured to a shaft or bar 10 which is journaled in the bracket 11 carried by the front angle piece 12 of the gate 5. The uppermost latch 8 is shown in detail in Fig. 4 and is different from the latch 9 in the addition of stop ears 45 13. The latches 8 and 9 are bifurcated, thus providing fingers 14 and 15 which are rounded at their outer ends, enabling the latches to readily rock into or out of engagement with the bar or rod 7. The upper-

50 most latch 8 has a notch 16. Pivoted at 17 to the front angle piece 12 is a lever 18 which is retracted by spring 19 connected to it and to the angle piece 12. A locking

bolt 20 pivoted to the lever at 21 and adapted to slide through an opening 22 in the web 55 of the angle piece 12 has its free end arranged to enter the notch 16 or to engage either of the lugs or ears 13. When the gate is closed, the notch 16 comes in line with the locking bolt 20, which thereupon 60 snaps into said notch and locks the latches 8 and 9 and the rod 10 against turning, and as these are then engaged with the rod 7, as shown in Fig. 4, the gate is locked whether it be in its lowered position, as 65 shown in Fig. 1, or, in its raised position, as shown in Fig. 2. On pulling back the lever 18 to disengage the bolt 20, from the notch 16, the latches 8 and 9 are freed and the gate may then be swung open, but as 70 the latch 8 turns, one of the ears 13 is arrested by engagement with the projecting end of the bolt 20 so that the latches 8 and 9 are prevented from turning so far that they will not reengage with the rod 7. If 75 no abutment was provided, these latches would turn out of proper position. Any suitable wire, cable, chain or other flexible connection 23 may be connected to the lever 18 and to the angle piece 24 at the heel of 80 the gate to constitute means for pulling the lever 18 from either side of the gate and from any point thereof so that the gate may be unlatched from either side thereof whether it is raised or lowered. 85

To elevate and lower the gate there may be provided the following devices: a bracket 25, an angle bar 24, having sheave 26; flexible connection 27 secured at 28; a locking lever 29 pivoted at 30 and having crooked 90 end 31.

The connection 27 is fastened to lever 29 at 32. The end 31 can be engaged with wire or rod 33 to hold the gate raised, as shown in Fig. 2.

95 The present application is a continuation or division of Serial No. 25,553, gates, filed May 3, 1915 by Alouis L. Winnega, deceased.

Having thus described the invention, what 100 is claimed as new and desired to be secured by Letters Patent, is:

In a gate latch, the combination with a latching rod or keeper, of upper and lower horizontally disposed bifurcated latches, a 105 rod or shaft which carries said latches and

by which they are rockably mounted to move in unison in a horizontal plane, one of said latches being provided with a notch and with lugs or shoulders on opposite sides of
5 said notch, and a manually retractable slide-able locking bolt adapted to be received in the notch to lock the latches or to engage

one or the other of the lugs to limit the lateral swinging of the latches.

In testimony whereof, I hereunto affix my 10
signature.

LILY M. WINNEGA,
Administratrix of the estate of Louis L.
Winnega, deceased.
